UNITED STATES PATENT OFFICE.

JENS P. NIELSEN, OF EUGENE, OREGON.

ART OF MAKING SWIVEL-AXLES.

1,179,134.

Specification of Letters Patent. Patented Apr. 11, 1916.

Application filed October 9, 1915. Serial No. 55,031.

To all whom it may concern:

Be it known that I, JENS P. NIELSEN, a citizen of the United States of America, and a resident of Eugene, county of Lane, State of Oregon, have invented certain new and useful Improvements in the Art of Making Swivel-Axles, of which the following is a full and clear specification, reference being had to the accompanying drawings, in which—

Figure 1 is a side elevation, and Fig. 2 a longitudinal sectional view showing my invention applied to a car axle, in which the swivel is arranged in the hub of one of the wheels; Fig. 3 is a transverse section on the line 4—4 of Fig. 1 showing the method of inserting the bars or rods which constitute the locking ring; Fig. 4 is a sectional view on the line 4—4 of Fig. 2 showing the locking ring completed and in operative position; Fig. 5 is a side elevation showing the manner of applying my invention to a car axle divided midway the wheels; Fig. 6 is a view partly in side elevation and partly in vertical section of the swivel shown in Fig. 5; Fig. 7 is a view similar to Fig. 6 showing the swivel as used on an old axle which is severed midway its length and connected by a twin-socket insert; and Fig. 8 is a vertical sectional view showing my improved swivel in a structure adapted for many uses.

The object of this invention is to provide a method of making a swivel coupling for axles and shafts which will produce a coupling of simple construction and have a high degree of durability and accuracy in operation, as more fully hereinafter set forth.

In its preferred form, my invention is embodied in two relatively rotatable members *a* and *b*, the former member being provided with a pivot or stub shaft *c* and the latter member being provided with a socket *d* in which the pivot *c* has a nice rotatable fit, the member *a* being provided with an annular shoulder *e* which abuts against the end face of the socket *d*. The pivot is provided with an annular groove *f*, which groove is provided with a shoulder *g* which faces outwardly, that is, toward the shoulder *e*. The interior of the socket is provided with an annular groove coincident with the groove *f*, this socket groove being provided with an annular shoulder *h* facing inwardly, that is, toward the shoulder *g*. An annular ring *h'* is fitted nicely but rotatively within

filling these grooves and having its inner edge abutting against the shoulder *g* and its outer edge against the shoulder *h*. It will be seen that the ring *h'* serves to lock the pivot in the socket and at the same time permit a free rotation thereof, whereby the two members *a* and *b* shall have a relative rotation. Suitable oil holes *i* are provided for oiling the bearing surfaces of the pivot at either side of the groove, but it will be understood, of course, that the oil deposited in these holes will not only work into the grooves but will also work around the end of the pivot and onto the bearing face of the shoulder *e*.

In assembling the parts, the locking ring is shaped into ring form in the act of inserting it into the corresponding grooves. In Fig. 3 I illustrate the manner of inserting the locking ring. Before insertion the locking ring consists of two straight bars of hard metal, preferably steel. These bars are heated to a degree sufficient to permit ready bending and are simultaneously forced into the grooves through opposite holes *j* formed in the socket member. The holes are slightly tangential so that as the bars are inserted they are bent around the pivot in the same direction. The bars are of such length that when they are completely inserted, their ends meet in the grooves and thus constitute virtually a single locking ring. During the act of inserting the rods, the pivot member may be allowed to rotate and thus facilitate the bending of the heated bars. The bars are of such dimensions with respect to the grooves in the socket and the pivot that when they cool the locking ring will have a nice rotative fit within the grooves, so that the members *a* and *b* will have a relative rotation with respect to each other. After the bars are fully inserted, the holes *j* are plugged with pieces of steel *k* in such manner that the plugs will not jar out; and to avoid any possibility of these plugs biting into the locking ring, I place in the bottoms of the holes *j*, against the outer surface of the locking ring, pieces *l* of wood or other cushioning or packing material.

In all of the figures, except Fig. 8, the locking ring is shown rhomboidal in cross section. This is the form I prefer, but, as shown in Fig. 8, this ring may be made rectangular in cross section if desired.

This invention may be used on all kinds

2
its highest utility in connection with railroad car axles, in that by the use of the invention in such axles the wheel treads may be made flat instead of conical and thus 5 increase the life of the rails and the tractive power of the wheels.

So far as I have at this time studied and developed this invention, I can see no reason why the invention cannot be carried out 10 by forming the locking ring of more than two sections or simply of a single bar, and it will be understood, therefore, that I desire to avoid restricting my claims to the use of the two-section method I have illustrated 15 and described. It will be understood that a feature of importance in my method of assembling the device lies in the idea of employing the confines of the annular channel formed by the coinciding grooves to properly 20 bend the ring to the proper curvature during the act of inserting it, whereby the ring will have exactly the curvature needed and whereby also I may be enabled to make the ring of a hard metal that will possess 25 the highest degree of wearing qualities.

Having thus described my invention, what I claim is:

1. The method herein described of assembling axle swivels, in which one member 30 is provided with a pivot entering a socket of the other member and is locked therein by an annular hard-metal ring lying in corresponding grooves in the pivot and the interior of the socket, consisting in simultaneously forming and positioning the ring 35 by inserting the same in bar form through a hole in the wall of the socket, the bar being heated to bending temperature and being caused to follow the curvature of the

pivot by the confines of the groove when 40 thus forced into the socket, substantially as set forth.

2. The method herein described of assembling axle swivels, in which one member is provided with a pivot entering a 45 socket of the other member and is locked therein by an annular hard-metal ring lying in corresponding grooves in the pivot and the interior of the socket, consisting in simultaneously forming and positioning the 50 ring by inserting the same in sectional bar form through a plurality of holes in the wall of the socket, the bar being heated to bending temperature and being caused to follow the curvature of the pivot by the confines of the groove when 55 thus forced into the socket, substantially as set forth.

3. The method herein described of assembling axle swivels, in which one member is provided with a pivot entering a socket 60 of the other member and is locked therein by an annular hard-metal ring lying in corresponding grooves in the pivot and the interior of the socket, consisting in simultaneously forming and positioning the ring 65 by inserting the same in bar form through a hole in the wall of the socket, the bar being heated to bending temperature and being caused to follow the curvature of the pivot by the confines of the groove when 70 thus forced into the socket, and then plugging the hole in the socket to completely confine and inclose the locking ring thus formed.

In testimony whereof I hereunto affix my 75 signature.

JENS P. NIELSEN.
